C. H. NORDELL

MEANS FOR FEEDING FLUID BY INTERMITTENT CHANGES OF FLUID PRESSURE

Filed Sept. 12, 1922

UNITED STATES PATENT OFFICE.

CARL H. NORDELL, OF FORT WAYNE, INDIANA, ASSIGNOR TO THE PERMUTIT COMPANY, A CORPORATION OF DELAWARE.

MEANS FOR FEEDING FLUID BY INTERMITTENT CHANGES OF FLUID PRESSURE.

Application filed September 12, 1922. Serial No. 587,837.

My invention relates to devices for feeding fluids by intermittent change of fluid pressure.

Such devices may be adapted to a wide range of uses without departing from the spirit of my invention.

Heretofore great difficulty has been experienced in feeding fluids continuously in very small quantities because such feeding must be through minute apertures which readily become clogged, destroying the accuracy or even the continuity of feeding and requiring continuous supervision to maintain operation. Obviously, such feeding means would be totally inadequate for use in connection with automatically operated apparatus.

Most requirements are fully met by intermittent feeding of small charges of fluid to be fed, providing the intervals between charges are short and the charges are relatively uniform in amount. My invention consists in such a method of intermittent feeding and apparatus for carrying this method into effect.

The particular embodiment of my invention selected for illustration is a brine feeding device, adapted for use on automatic water softening apparatus such as that illustrated and described in my co-pending applications Serial No. 487,465 filed July 25th, 1921, Patent 1,608,661, Nov. 30, 1926, Serial No. 561,095 filed May 15th, 1922 and Serial No. 585,045 filed August 29th, 1922.

Figure 1 shows the salt tank and feeding device in vertical axial section, the piston and valve being at rest, with suitable pipe connections therefor, and

Fig. 2, a detail, is an enlarged view in vertical axial section of the lower portion of the feeder, with the piston and check valve in partly raised position.

Referring now to the drawings, 1 is a salt tank, with a salt charging opening, 2, and a leak tight cover, 3, therefor. A pipe, 4, preferably with a valve, 4^a, feeds water from a source of supply (not shown) to the salt tank, 1. A screen, 5, at the bottom of the salt tank, 1, insures clear brine reaching the outlet, 6, by keeping out salt and dirt. A pipe, 7, conveys brine from the outlet, 6, to the brine feeder.

The brine feeder consists of an upper cas-

ing, 8, cap, 9, lower casing, 10, stuffing box, 11, and the parts enclosed in and connected therewith. The pipe, 7, conveys brine into the chamber, 19, of the casing, 10, under the loose fitting free floating cylindrical slug piston, 12.

A rod, 13, adjustable as to height, and secured in the desired position by set screw, 14, determines the stroke of the piston, 12. An axially bored valve seat, 15, is secured in the casing and a ball, 17, or other check valve, rests upon 15 and closes the opening, 16, therethru.

A pipe, 18, preferably having a valve, 18^a, provides an outlet for brine from the feeder.

It will be understood that both salt tank and brine feeder are constantly under pressure; but that at predetermined intervals there is a change of pressure as hereinafter described; such change being caused by a means not a part of this invention and not shown herein.

The operation of the device is as follows beginning with the elements in the position shown in Fig. 1:—

Either by a temporary decrease of pressure in the pipe, 18, or temporary increase of pressure in the pipe, 4, a charge of brine is forwarded thru the pipe, 7, from the tank, 1, into the chamber, 19, below the piston, 12, causing the piston to rise and discharge the brine already in the chamber, 20, through the opening, 16, unseating the valve, 17, discharging said brine into the chamber, 21, and forcing a part of the brine already in the chamber, 21, out to service through the pipe, 18.

Upon return to normal of the pressure in the system, the valve, 17, seats, preventing back flow of the brine from chamber, 21, to chamber, 20, the piston, 12, falls, allowing the brine below it to pass between its cylindrical surface and the inner wall of the casing, 10, into the chamber, 20; when all parts are again in the position shown in Fig. 1.

I claim as my invention and desire to secure by Letters Patent of the United States:—

Liquid feeding means comprising a vertically disposed cylinder, a loosely fitting piston slug disposed therein, means formed in the cylinder for admitting fluid to the un-

derside of the slug, means positioned above said slug operative to permit the escape of fluid from said cylinder, an adjustable stop member for limiting the stroke of said slug, a closure for said liquid escape means, said closure being forced away from said escape means when the piston slug moves up-

wardly, and being positioned to close said escape means when the slug moves down-
wardly.

10

In testimony whereof I have hereunto set my hand.

CARL H. NORDELL.
